MOTOR-CONTROL SYSTEM.

Application filed January 3, 1923, Serial No. 611,264, and in Great Britain January 11, 1922.

Our invention relates to control systems and it has special relation to control systems in which the acceleration of a motor by short-circuiting a series resistor is automatically effected by means of electrically actuated switches or contactors. In these systems, the operation of the switches is usually controlled in accordance with the armature current of the motor by a current-limiting relay, whereby the switches are prevented from operating until the main armature current falls to a predetermined safe value.

An object of our invention is to provide, in an automatic control system employing a current-limiting relay, means whereby, under abnormal conditions, the necessary accelerating steps may be effected independently of the normal relay action.

Another object of our invention is to provide, in a system of the class described above, means whereby certain circuits normally controlled by a current-limiting relay may be controlled independently of the current relay.

In systems of the class referred to, difficulty is sometimes experienced under severe conditions of track or gradient in starting the train. For example, if one motor on a locomotive is out of condition, the accelerating current for which the relay is set may be insufficient to effect the starting of the train, and the relay will, therefore, hold the equipment on the first accelerating notch or step, so that the other contactors controlling further notches or steps cannot close.

According to our invention, a push-button switch, under the control of the driver, is arranged in such manner that the contactor circuits, or the energizing circuits of the electrically operated switches that effect the accelerating steps, may be directly energized independently of the operation of the current-limiting relay even if the relay does not operate by reason of a relatively high armature current.

In order that the invention may be clearly understood, it will now be described with reference to the accompanying drawings, in which

Fig. 1 is a diagrammatic representation

of a main or motor circuit including a variable resistor and a current-limiting relay,

Fig. 2 is a diagrammatic representation of our control circuits and control devices for automatically or manually effecting acceleration of the motor shown in Fig. 1, and

Fig. 3 is a diagrammatic representation of a modification of part of the circuits and devices shown in Fig. 2.

The main motor circuit illustrated in Fig. 1 comprises an armature 1 and field winding 2 of a series motor which may be connected to a supply conductor 3 and ground G through a variable resistor 5, a line switch 6, and a current-limiting relay 29. Sections 7, 8 and 9 of the variable resistor 5 are adapted to be short-circuited respectively by switches 10, 11 and 12, which are controlled respectively by coils 14, 15 and 16.

Referring to Fig. 2, the control system here shown comprises the supply conductor 3, a plurality of coils 13, 14, 15 and 16 for operating respectively the main switches 6, 10, 11 and 12, shown in Fig. 1, and certain interlocking switches, in a manner to be hereinafter set forth, together with a master controller 19, having three positions *a*, *b* and *c*, which acts in conjunction with a current-limiting relay 29 to successively energize the coils 13, 14, 15 and 16. A push-button switch 49 is connected to one of the stationary contact members of the relay 29, for a purpose to be subsequently set forth.

The current-limiting relay hereinafter described in the specification and illustrated in the drawing is preferably of the type shown in Patent No. 1,077,972, granted to E. R. Carichoff, Nov. 11, 1913, to which reference may be made for a detailed description.

The relay 29 comprises essentially a plurality of coils 27 and 28 which, during certain operative positions of the master controller 19 respectively control the operation of plungers or cores 53 and 54. A plurality of movable contact members 30 and 31 cooperate with the plungers 53 and 54 to bridge stationary contact members 32 and 33, and 34 and 35, respectively. A coil 36 of the relay 29 is connected in series relation with the main motor circuit, as shown in Fig. 1, and is adapted, when the motor current ex-

ceeds a predetermined value, to retain either of the movable contact members 30 and 31 in its open position after actuation thereto by its own coil 27 or 28, irrespective of the continuance or discontinuance of the energization of that coil.

Assuming the various switches and other apparatus to occupy the illustrated inoperative positions, the operation of the automatic accelerating system illustrated in Fig. 2 is as follows: When the master controller 19 is moved from the off position *a* to the initial operative position *b*, a circuit will be established from supply conductor 3 through contact segment 20 of the controller 19, control finger 21, coil 13, of switch 6 and interlock switches 22, 23 and 24 of switches 10, 11 and 12, respectively, to ground G. In this manner, the line switch 6 is closed by reason of the energization of its operating coil 13 and the motor is connected to the supply conductor 3 and ground G, through the accelerating resistor 5.

If the master controller 19 is actuated to its second operative position *c*, a circuit is established to energize coil 14 of contactor switch 10, which is thus actuated to short-circuit a section 7 of the accelerating resistor 5. The circuit in question extends from supply conductor 3 through segment 20 of the controller 19, control finger 25 and common terminal 26 of relay 29. Since the movable contact members 30 and 31 of the relay 29 are at this moment in their lower positions, and since the interlock switches 37 and 38 of switches 6 and 10, respectively, are closed and the interlock switch 45 of switch 11 is open, the coil 27 only of the relay 29 will be energized and the contact member 30 thereof will be raised. The circuit being described thus continues from the common relay terminal 26 through coil 27, contact members 34, 31 and 35, interlock switches 37 and 38, actuating coil 14 of contactor switch 10, conductor 39, and interlock switches 23 and 24 to ground G. The resistance step 7 being thus short circuited, the motor will accelerate to a given speed, in accordance with familiar principles.

By reason of the closure of contactor switch 10, interlock switches 22 and 38 will open and interlock switches 40 and 41 will close, so that the energization of coil 14 of the contactor switch 10 is transferred through interlock switch 40 to the circuit by means of which the line-switch actuating coil 13 is energized, this circuit extending as follows: From supply conductor 3 through contact segment 20, of controller 19, contact finger 21 thereof, coil 13, interlock switch 40, actuating coil 14, conductor 39, and interlock switches 23 and 24 to ground G. Since interlock switch 38 opens with contactor switch 10, coil 27 of relay 29 will be de-energized, but the contact mem-

ber 30 thereof is in the meantime held in its upper position by reason of the flux produced by series coil 36 of the relay 29, which coil is carrying the same current as the main motor. As soon as this current falls to the proper safe value, the movable contact member 30 of the relay 29 will drop, so that current will flow through the coil 28 of the relay 29, and the movable contact member 31 thereof will assume its upper position. 75

A circuit will thereupon be established from the contact member 32 of relay 29, through interlock switches 41 and 42, actuating coil 15 of contactor switch 11, conductor 44, and interlock switch 24 to ground G. The circuit previously traced through the actuating coil 13, interlock switch 40, actuating coil 14, conductor 39 and interlock switches 23 and 24 is still energized. Upon the closure of contactor switch 11, the interlock switches 23 and 42 immediately open and the interlock switches 43 and 45 immediately close, so that in the manner already described, in connection with the energization of the actuating coil 14, the coil 90 15 is transferred to a circuit which traverses coil 13, interlock switch 40, coil 14, interlock switch 43, coil 15, conductor 44 and interlock switch 24 to ground 18. Since the closure of the switch 11 short circuits the resistor 8, the current in the motor circuit is increased. 95

The relatively high current traversing the motor 1 again effects the lifting of the relay contact member 30 by reason of the series coil 36, but, in the meantime, a circuit from stationary contact member 35 through interlock switches 45 and 46 and actuating coil 16 of the contactor switch 12 to ground G, is prepared. This circuit is obviously 105 completed, when the armature current falls to the proper value, by means of contact member 31 of relay member 29, whereupon the relay coil 27 is energized and its contact member 30 lifted. A circuit is thus established from coil 27 through movable contact member 31 of relay 29, interlock switches 45 and 46, actuating coil 16 of switch 12 and conductor 47 to ground G. 110

Upon the closure of contactor switch 12, 115 interlock switches 24 and 46 immediately open and interlock switch 48 closes, so that coil 16 is transferred to the previously traced circuit from the actuating coil 15, which is already energized through conductor 44, interlock switch 48, actuating coil 16 and conductor 47 to ground G. The resistor 9 is cut out of the motor circuit and the current in the motor circuit temporarily increased. 120

Although only three resistance steps and only a single motor have been shown and described, it will be readily understood that the circuits illustrated in Fig. 2 may be extended indefinitely, and that our invention may be applied to other types of control. 125 130

In Fig. 2, the reference character 52 represents substitutional resistors, the introduction of which into the control circuits is usually necessary for the efficient working of such a control system, as is well known.

In the above-described control system, if the master controller 19 is moved first to the notch *b*, and then to the notch *c*, the section 7 of the resistor will be short-circuited by the closure of the contactor switch 10 in the manner hereinbefore described. Further automatic progression may be prevented by reason of the train being on a gradient or by reasons of other serious conditions of track, in which case the relay contact member 30 will be held up indefinitely by reason of the current in the series coil 36 of the relay 29.

Under such conditions, further operation may be manually controlled as follows: If the push-button switch 49 is depressed, the circuit of the actuating coil 15 of contactor switch 11 will be energized by a circuit traversing interlock switches 41 and 42 and contact members 35 and 31, as the latter has remained in its lower position.

Upon releasing the push button switch 49, the circuit through interlock switches 41 and 42 will be broken and a circuit will be established through interlock switches 45 and 46 and coil 16 to ground *G*, so that coil 16 of contactor switch 12 will be energized, thereby further accelerating the train.

With the above described arrangement, it will be seen that alternate depressing and releasing of the push button switch 49 enables the otherwise automatic starting operation to be effected under manual control up to the full speed condition.

In certain instances, however, the operation of one extra step manually will be sufficient to start the train and according to the modification illustrated in Fig. 3, a push button switch 51 is so arranged as to normally close the first of the contactor coil-energizing circuits connected with the relay contact member 35 and when depressed, to shunt the contact members 32 and 33, pertaining to the contact member 30 and coil 28, by means of which the second energizing circuit is controlled, the first energizing circuit being at the same time broken.

With this arrangement, it will be seen that when the push-button 51 is depressed, the coil 28, controlling the movable contact member 31, which governs the circuit that is broken by the depression of the button, is energized so that the said first circuit, extending from the contact member 35, is de-energized, the relay contact member 31 being held up until the current in the series coil 36 falls to the value to which the relay is set. The release of the push button switch 51 will not, therefore, effect the closure of any further contactor switches until the contact

member 31 falls. Alternate automatic and non-automatic operation of the contactor switches is thus obtained.

We do not wish to be restricted to the specific circuit connections or arrangements of parts herein set forth, as various modifications thereof may be made within the spirit and scope of our invention. We desire, therefore, that only such limitations shall be imposed as are indicated in the appended claims.

We claim as our invention:

1. A control system comprising a motor, an accelerating relay therefor, provided with a plurality of movable members respectively corresponding to successive increments of acceleration and manually operative means for effecting the continuance of said acceleration upon failure of said relay to operate at any stage of said acceleration.

2. A control system comprising a motor, a relay for automatically accelerating said motor comprising a pair of switches, a pair of coils for operating said switches, a current coil adapted, under predetermined conditions of motor current, to prevent the closing of either of said switches, and manually controlled means for effecting the continuance of said acceleration upon failure of one of said switches to close.

3. A control system comprising a plurality of coils, a plurality of circuits for successively energizing said coils, a relay having a pair of actuating coils, a pair of movable cores co-operating respectively with said coils, a pair of switches respectively actuated by said cores and adapted to control said circuits, a third coil located between said pair of coils and adapted under predetermined conditions to prevent the closing of either of said switches, and manually controlled means for successively energizing said circuits on failure of one of said switches to close.

4. A control system comprising a plurality of circuits adapted to respectively energize a plurality of actuating coils, a relay for automatically effecting the energization of said circuits successively, comprising a pair of actuating coils, a pair of switches operated by said last-mentioned coils and adapted to successively close said circuits, a third coil located between said pair of coils and adapted, under predetermined conditions to prevent either of said switches from closing, and manually controlled means for successively energizing said circuits independently of the normal operation of said relay.

5. A control system comprising a pair of switches having respectively a plurality of stationary contact members and a movable contact member co-operating therewith, an operating coil for each of said switches, having one terminal connected to one of said stationary contact members of the other switch,

whereby a current traversing the contact members of one of said switches will energize the operating coil of the other of said switches to open said other switch, a plurality of circuits connected respectively to the other stationary contact members of said switches, means for opening and closing said circuits successively, a current coil adapted, upon energization by predetermined values of current, to hold either of said switches in

the open position, and manually operated means whereby said circuits may be successively energized upon failure of one of said switches to close.

In testimony whereof, we have hereunto ¹⁵ subscribed our names this 20th day of December, 1922.

ROBERT BROOKS.
EDWARD HUGH CROFT.
